UNITED STATES PATENT OFFICE.

ALFRED H. BAMBERGER, OF NEW YORK, N. Y.

DESIGN FOR A DISPLAY-STAND.

47,575.

Specification for Design.

Patented July 20, 1915.

Application filed March 18, 1915. Serial No. 15,332. Term of patent 3½ years.

To all whom it may concern:

Be it known that I, ALFRED H. BAMBERGER, a citizen of the United States, and resident of the borough of Manhattan, city, county, and State of New York, have invented a new, original, and ornamental Design for Display-Stands, of which the following is a specification.

Reference is to be had to the accompanying drawing in which—

Figure 1 is a perspective view of a display stand illustrating my new design and Fig. 2 is a plan view thereof.

The design comprises circular top and bottom members spaced apart and secured together by means of uprights, the top member being provided with a plurality of rela-

tively large openings, and the bottom member having a plurality of smaller openings or recesses in axial alignment with said relatively large openings. Projections preferably corresponding in cross-section to the shape of the uprights extend downwardly beyond the bottom member and upwardly beyond the top member in registry with said uprights.

I claim:

The ornamental design for a display stand as shown and described.

ALFRED H. BAMBERGER.
